(57) **CLAIM**

The ornamental design for an air freshener, as shown and described.

DESCRIPTION

FIG. 1 is a left front top perspective view of an air freshener, which air freshener is shown with a liquid fragrance insert package installed therein;

FIG. 2 is a left rear bottom perspective view of the air freshener of FIG. 1;

FIG. 3 is front elevational view of the air freshener of FIG. 1;

FIG. 4 is a rear elevational view of the air freshener of FIG. 1;

FIG. 5 is a top view of the air freshener of FIG. 1;

FIG. 6 is a bottom view of the air freshener of FIG. 1;

FIG. 7 is a left side view of the air freshener of FIG. 1;

FIG. 8 is right side view of the air freshener of FIG. 1;

FIG. 9 is a left front top perspective view of an air freshener;

FIG. 10 is a left rear bottom perspective view of the air freshener of FIG. 9;

FIG. 11 is a front elevational view of the air freshener of FIG. 9;

FIG. 12 is a rear elevational view of the air freshener of FIG. 9;

FIG. 13 is a top view of the air freshener of FIG. 9;

FIG. 14 is a bottom view of the air freshener of FIG. 9;

FIG. 15 is a left side view of the air freshener of FIG. 9; and,

FIG. 16 is right side view of the air freshener of FIG. 9. The broken lines shown in the figures are for the purpose of illustrating portions of the air freshener and form no part of the claimed design.

1 Claim, 8 Drawing Sheets
